(57) **CLAIM**

The ornamental design for a pair of complementary bottles, as shown and described.

DESCRIPTION

FIG. 1 is a right side elevational view of a first bottle in a pair of complementary bottles of the claimed design, shown separately for clarity of illustration;

FIG. 2 is a rear elevational view thereof;

FIG. 3 is a front elevational view thereof;

FIG. 4 is a top plan view thereof;

FIG. 5 is a bottom plan view thereof;

FIG. 6 is a left side elevational view thereof;

FIG. 7 is a left side elevational view of a second bottle in a pair of complementary bottles of the claimed design, shown separately for clarity of illustration;

FIG. 8 is a front elevational view thereof;

FIG. 9 is a rear elevational view thereof;

FIG. 10 is a top plan view thereof;

FIG. 11 is a bottom plan view thereof;

FIG. 12 is a right side elevational view thereof; and,

FIG. 13 is a front elevational view of the pair of complementary bottles shown in complementary position.
